UNITED STATES PATENT OFFICE.

JAMES M. DODGE, OF PHILADELPHIA, PENNSYLVANIA.

STAIR-LIFT.

SPECIFICATION forming part of Letters Patent No. 639,154, dated December 12, 1899.

Application filed August 5, 1899, Serial No. 726,221. (No model.)

To all whom it may concern:

Be it known that I, JAMES M. DODGE, a citizen of the United States, residing in Philadelphia, Pennsylvania, have invented certain 5 Improvements in Stair-Lifts, of which the following is a specification.

My invention relates to certain improvements in endless-belt conveyers which are so guided on the carrying run as to form the treads and risers of a moving stairway, or, 10 more properly, a stair-lift.

The object of my invention is to so construct the belt that it can be flexed not only at the pivot-points to form the treads and 15 risers, but also between these points, for the purpose which I will describe hereinafter.

Referring to the accompanying drawings, Figure 1 is a sectional elevation of my improved stair-lift. Fig. 2 is a perspective view 20 in diagram. Fig. 3 is an enlarged sectional view showing a portion of one step and adjoining risers. Fig. 4 is a plan view of Fig. 3. Fig. 5 is a view showing the belt passing around the upper roller. Fig. 6 is a plan 25 view of a portion of the upper roller. Fig. 7 is an enlarged sectional view on the line 77, Fig. 1. Figs. 8, 9, and 10 are views of different forms of links, and Figs. 11 and 12 are views showing the form of links used at the 30 front edge of tread.

A is an endless belt, made up in the present instance of a series of links *a*, hinged together by pins *b*, passing through depending portions *a'* of the links, so as to form a continuous surface. These links are capable of 35 moving on their pivots to a certain extent, for the purpose fully described hereinafter. Arranged at given distances apart are a series of pivots *B*. These pivots carry at their outer 40 ends rollers or wheels which are adapted to fixed guideways. The pivots are secured to the links of the belt—in the present instance by rings *b'*. These rings encircle the pivots and have perforated projections through 45 which the pivot-pins *b* pass. The pivots are preferably secured to two pivot-pins, as shown in Fig. 3. The structure therefore consists of an endless belt having pivots at given distances apart, the pivots in the present instance 50 extending beyond the edges of the belt, and the belt is so constructed as to be capable of being flexed between the pivots.

D D' are guideways for the pivots. These two guideways merge into each other at either end of the stair-lift and connect with a return-guide D², as clearly shown in Fig. 1.

E is a gap sprocket-wheel situated at the upper end of the stair-lift. This wheel is small and engages with the pivot-pins of each link. The pivot-rods *B* rest in the gap, as 60 shown in Fig. 5. The sprocket-wheel is driven in any suitable manner.

At the lower end of the stair-lift I preferably provide a drum *F*, which is, in fact, an idler and is simply for the purpose of carrying the belt from the return-guideway to the elevating-guideways. Recesses are formed in this drum for the reception of the pivots and preferably for the reception of the pivot-pins of the links.

It will be noticed that the upper floor or landing I is arranged slightly below the upper surface of the belt as it passes around the roller, so that it is impossible for anything to catch between the belt and the floor. The 75 lower floor I' is slightly below the level of the belt, but may be on the same plane.

The guideway D' has a channel *d'*, into which extends the end of the pivots *B'*, which may be provided with rollers. By this arrangement the pivots *B* will pass through the guideway D, while the pivots *B'* will pass through the guideway D', so as to form the steps. The deflection takes place at a point at or near the lower floor, and the rollers are 85 so arranged that alternate pivots travel in the different guideways, so that treads and risers are formed. For instance, the rollers at the outer edge of the treads travel in the guideway D, while the rollers at the inner edge of the 90 treads travel in the guideway D'. Thus it will be seen that as the belt passes from the idler-drum *F* first a tread is formed, then a riser, then a tread, and so on, and a person can step onto the stair-lift during the forming of the treads. The risers always being 95 at an angle will prevent a person stepping on that portion of the belt.

It will be noticed that the riser-sections do not assume a vertical position, as in an ordinary stairway, but preferably remain in an inclined position, as shown in Fig. 1. By this arrangement the treads can be made narrow; but the space between the treads is in-

creased, so as to give sufficient room between one passenger and another.

When the tread upon which the passenger is carried reaches the top of the stair-lift, the 5 passenger can readily step onto the landing and the belt, which is flexible between the pivots, will disappear around the gap sprocket-wheel and return, thus taking up very little room at the upper landing.

10 I preferably form the belt of a series of metallic links of the forms shown in Figs. 8, 9, 10, 11, and 12, and I may make these either of forged or malleable castings. Each link consists of a body portion *a* and depending 15 wings *a'* at each side, the wings being of the form shown, so that they will lap. The pivot-pins *b* pass through openings in the wings. Each link has a tongue *a²*, which underlaps the body portion *a* of the adjoining link, so 20 that the belt will have a continuous surface. The tongues are so proportioned that they will underlap the depending link when the belt turns around the gap sprocket-wheel *E*. The link shown in Fig. 8 is that used for the 25 body of the belt between the pivots *B* and *B'*, while the pair of links shown in Figs. 9 and 10 are used at the junction of the inner end of the tread and the lower portion of the riser, as indicated at 1 and 2, Fig. 3. The 30 edges of the link 2 are cut away and the surface *a³* of the link 1 is beveled, so that when the riser is formed the link 2 can pass over the link 1, as indicated in Fig. 3. The links, as shown in Figs. 11 and 12, (indicated 35 by the numerals 3 and 4 in Fig. 3,) are placed at the junction of the riser and the outer edge of the tread, and the tongue *a²* of the link 3 extends the full width of the tread, and the depending portions *a'* of the link 4 are 40 undercut at *a⁴* to receive this tongue, so that there will be no opening at the outer edge of the tread, and the tongue is of sufficient length to underlap the adjoining link when turning around the gap sprocket-wheel *E*. 45 It will be understood that other forms of links may be used without departing from the main feature of my invention. Thus it will be seen that the endless belt is made up of a number of links coupled together by the 50 pins *b*, the link at the joints of the treads with the risers being so formed that there will be as little opening as possible at these points.

It will be understood that in some instances 55 instead of making the belt of pivoted links, as shown, it may be made of any flexible material, such as leather, and so formed that the treads will support the load; but I prefer to use the links, as I can form them in such 60 a manner that they will readily yield in one direction, but be perfectly rigid and support the load in the opposite direction, and, furthermore, the construction is comparatively cheap and substantial.

65 I claim as my invention—

1. In a stair-lift, the combination of a series of treads and risers hinged together, each

tread and riser being flexible, substantially as described.

2. In a stair-lift, the combination of a series of treads and risers hinged together, each tread and riser being flexible, and a head-wheel around which the treads and risers are flexed in passing from one run to the other, substantially as described. 75

3. In a stair-lift, the combination of a series of treads and risers, each tread and riser being flexible, a small wheel at one end of the stair-lift around which both the treads and risers are flexed, and a fixed platform in close 80 proximity to the treads and risers as they pass around the wheel, substantially as described.

4. In a stair-lift, the combination of an endless belt made up of a series of flexible treads and risers pivoted together, guides for the 85 pivots, a drum at the lower end of the stairway around which the treads and risers are flexed, a platform at the drum in close proximity to the surface of the belt, a small wheel at the head of the stair-lift around which the 90 treads and risers are flexed, and a fixed platform in close proximity to the belt at the point where it passes around the head-wheel, substantially as described. 95

5. In a stair-lift, the combination of an endless band having pivots at given distances apart to form treads and risers, said band being flexible between the pivots only in a vertical direction, whereby the band can be flexed around guide-wheels, substantially as 100 described.

6. The combination in a stair-lift, of an endless flexible band, having pivots at given distances apart, two guideways, alternate pivots adapted to one guideway and the other pivots 105 adapted to the other guideway, said guideways merging into each other at each end of the stairway and communicating with the return-guideway, substantially as described.

7. In a stair-lift, the combination of an endless band made up of a series of short en-chained links pivoted at given distances apart, the bands being vertically flexible between the pivots, with guides whereby treads and risers are formed by guiding alternate pivots 110 out of line, substantially as described. 115

8. The combination in a stair-lift, of guideways, *D*, *D'*, *D²*, the guideways *D* *D'* merging into each other at the upper and lower portions of the stairway and communicating with 120 the return-guideway *D²*, an idler at the lower portion of the stair-lift, a sprocket-wheel at the upper portion of the stair-lift, and a flexible endless belt adapted to the rollers and 125 adapted to be flexed by the guideways, substantially as described.

9. In a stair-lift, the combination of an endless band having pivots at given distances apart, said band being flexible between the pivots, guides for the pivots, and a gap sprocket-wheel around which the band passes, the pivot-bars entering the gap in the sprocket-wheel, substantially as described. 130

10. The combination in a stair-lift, of an

endless flexible band having pivots at given distances apart, two guideways, alternate pivots adapted to one guideway and the other pivots adapted to the other guideway, said 5 guideways merging into each other at each end of the stairway and communicating with the return-guideway, a channel in one guideway into which one set of pivots extend, substantially as and for the purpose set forth.

10 11. In a stair-lift, the combination of guides, an endless belt having pivots at given distances apart and adapted to the guides, said guides being so formed that on the carrying run the endless belt will be so arranged that 15 the belt will be formed into treads and risers and the risers will be inclined throughout the carrying run of the stair-lift, whereby the horizontal distance between the steps will be increased, substantially as and for the purpose set forth.

20

12. In a stair-lift, the combination of guides, a series of treads and risers hinged together, forming an endless belt, means for driving said belt, each tread and riser being made up of a series of links hinged together so that the 25 said steps and risers will be flexible, the upper surface of each link being curved, a head-wheel around which the treads and risers are flexed, the curved surface of each link being such that a cylindrical surface will be formed 30 as the endless belt passes around the head-wheel, and a platform in close proximity to the belt, substantially as described.

In testimony whereof I have signed my name to this specification in the presence of 35 two subscribing witnesses.
